UNITED STATES PATENT OFFICE

DOLLIE McNEIL, OF LA FAYETTE, CALIFORNIA

DESIGN FOR A DOLL

Application filed April 29, 1929. Serial No. 31,038. Term of patent 7 years.

To all whom it may concern:

Be it known that I, DOLLIE McNEIL, a citizen of the United States, residing at La Fayette, in the county of Contra Costa and State of California, have invented a new, original, and ornamental Design for Dolls, of which the following is a specification, reference being had to the accompanying drawing, forming part thereof.

I claim:

The ornamental design for a doll as shown.

DOLLIE McNEIL.
